MIXER

Alfred W. Madl, Mequon, Wis., assignor to John Oster
Manufacturing Co., Milwaukee, Wis., a corporation of Wisconsin

Filed Jan. 7, 1965, Ser. No. 83,323

Term of patent 14 years

(Cl. D44—1)

FIG. 1 is a perspective view of a mixer embodying my design;

FIG. 2 is an enlarged front view thereof;

FIG. 3 is a top view thereof;

FIG. 4 is a side view thereof;

FIG. 5 is a rear view thereof; and

FIG. 6 is an enlarged fragmentary sectional view taken along the section line 6—6 of FIG. 2.

The dominant features of the design reside in those portions shown in full lines.

I claim:

The ornamental design for a mixer, as shown and described.
